DESIGN FOR A CONCRETE FINISHING TOOL

Nicola La Manca, Cumberland, Md.

Application December 20, 1941, Serial No. 104,753

Term of patent 7 years

To all whom it may concern:

Be it known that I, Nicola La Manca, a citizen of the United States, residing at Cumberland, in the county of Allegany and State of Maryland, have invented a new, original, and ornamental Design for a Concrete Finishing Tool, of which the following is a specification, reference being had to the accompanying drawing, forming part thereof.

Figure 1 is a wide elevational view of a concrete finishing tool, showing my new design.

Figure 2 is a top plan view thereof, and

Figure 3 is a sectional view taken on the line 3—3 of Figure 2.

I claim:

The ornamental design for a concrete finishing tool, as shown.

NICOLA LA MANCA.
